(57) **CLAIM**

The ornamental design of a hybrid duffel bag with flip cover concealed zipper, as shown and described.

DESCRIPTION

FIG. 1 is a front, right, top perspective view of a hybrid duffel bag with flip cover concealed zipper, illustrating the novel design.

FIG. 2 is a right side view thereof.

FIG. 3 is a left side view thereof.

FIG. 4 is a front view thereof.

FIG. 5 is a back view thereof.

FIG. 6 is a top view thereof.

FIG. 7 is a bottom view thereof; and,

FIG. 8 is a back, left, top perspective view thereof, with the flip cover opened, exposing the zipper, illustrating the novel design in detail.

The broken lines in the drawings illustrate unclaimed portions of the hybrid duffel bag with flip cover concealed zipper and form no part of the claimed design.
